UNITED STATES PATENT OFFICE.

KURT HARING, OF HERSFELD, GERMANY, ASSIGNOR TO THE CORPORATION OF
ANHYDAT-LEDER-WERKE, AKTIENGESELLSCHAFT, OF HERSFELD, GERMANY.

MANUFACTURE OF FIBROUS MATERIAL TO BE USED AS A SUBSTITUTE FOR LEATHER AND OTHER PURPOSES.

1,179,357.

Specification of Letters Patent. Patented Apr. 11, 1916.

No Drawing.

Application filed June 16, 1914. Serial No. 845,438.

To all whom it may concern:

Be it known that I, KURT HARING, citizen of the German Empire, and resident of Hersfeld, Hesse-Nassau, Germany, with 5 the post-office address Dippelstrasse 4, have invented new and useful Improvements in the Manufacture of Fibrous Material to be Used as a Substitute for Leather and other Purposes, of which the following is a specification.

My invention relates to the production of an impregnated fibrous material which has some of the characteristics of leather and which is capable of being used as a leather 15 substitute and for other purposes. The fibrous material may be of any kind and especially when it consists of a very thick felted fabric it can be impregnated in accordance with my invention so as to produce 20 a material so solid that it can hardly be distinguished from impregnated leather.

The object of my invention is to treat fibrous material with a solution of a suitable filling material, followed by treatment with 25 a fused mass of filling material, said last-mentioned filling material being soluble in the solvent for the filling material first used, and thus by what may be termed a diffusion process accomplish a more complete and 30 thorough impregnation of the fibrous material with filling material than can be obtained by previously known methods; moreover, by this diffusion process I can introduce into the fabric molten materials of consider- 35 able viscosity, such as could not be caused by previously known methods to penetrate thoroughly into the fiber.

In pending application, Serial No. 736,533, filed December 13, 1912, a process of treating 40 hides or leather, particularly chrome leather, is described, the steps of which process are in many respects similar to these of the present invention. The present invention, however, is not a tanning process 45 for hides or a leather treating process by which leather is given certain improved qualities or characteristics, but it is an improvement in the art of producing a fabric material of such a nature that it can be used, 50 for example, as leather substitute; my invention is therefore quite independent of and distinct from the invention of said pending application.

If it is desirable to impart to this fabric a special solidity it may first be saturated 55 with a solution of a derivative of cellulose, such as celluloid, cellite, cellon, the solvent dried out and the fabric again saturated with for instance a benzene solution of asphalt, and finally, in the saturated condition brought into a fused mass of petroleum pitch (the residues from the fractional distillation of petroleum also known as artificial asphalt or petrol goudron) which is also soluble in benzene, so that the fused 65 mass can be substituted for the solvent in the material and fill up all the pores. It is obvious that care should be taken that the cellulose derivative selected shall not be soluble in the solvent for the asphalt or 70 similar material, as otherwise the former would again be dissolved and thus in whole or in part removed from the fiber. It is obvious that the nature of the material to be impregnated as well as the impregnating 75 material may be varied. Instead of a felt a woven material of wool, cotton, hemp, linen, jute or the like, may be used, and instead of asphalt and petroleum pitch, resin, caoutchouc, gutta-percha, paraffins of high melting 80 point or the like may be employed. It is only necessary to observe the condition that the fused mass must be soluble in the solvent last used in the process so that the diffusion may be possible. It is also feasible to render 85 the impregnated material more or less hard by suitable additions. For instance if linseed oil varnish or a drying oil, such as linseed oil or poppy seed oil be added in small proportion to the fused mass, there will be 90 a gradual hardening of the whole owing to the action of atmospheric oxygen on this drying material. On the other hand by adding a fatty non-drying oil, such as a mineral oil or a cylinder oil, the impregnated 95 product may retain permanently a certain degree of softness and elasticity. In this manner by impregnating thin fabrics there may be made materials of greatest density resembling leather or waxed cloth, 100 whereas thicker fabrics may be made into driving belts of any desired length with only one seam, namely at the place where the ends are joined.

The following examples illustrate the invention: Pieces of felted fabric are laid in

a solution of petroleum pitch in an equal volume of benzene, and when fully saturated with this solution transferred to a molten mass consisting of 90-95 parts of petroleum pitch and 10-5 parts of linseed oil varnish. Instead of the linseed oil varnish there may be used a small addition of a mineral oil, for instance cylinder oil or a viscous paraffin. In this molten mass the fabric remains for about 24 hours, the initial temperature being about 85° C. and the final temperature 100°-110° C., whereby nearly all the benzene is gradually expelled from the fabric and its place taken by the molten mass. For further hardening the finished piece it may be allowed to remain for about 14 days. In this manner pieces of quite considerable thickness of a very solid material can be obtained, which is applicable for many purposes, for instance as a substitute for sole leather, for making driving belts, as a material for excluding water, as an electrical insulating material or the like. Again, felt is placed for several hours in a solution of cellulite in acetone. The acetone is then dried out, and the felt then placed in a 50% petroleum pitch-benzol solution, and then into a melt of petroleum pitch. Again, several pieces, or layers, of jute fabric are united by seams which are close together, to form a unitary body which is then laid into a 50% solution of mineral rubber in benzol, and impregnated therewith; thereafter the body is laid into a melt of petroleum pitch.

Now what I claim and desire to secure by Letters Patent is the following:

1. An improvement in the manufacture of fibrous material to be used as a substitute for leather and other purposes, which improvement consists in first introducing into the fabric to be impregnated a solution of a suitable filling material and then introducing the thus filled fabric into a fused mass adapted to be dissolved by the solvent used in the said solution substantially as described.

2. An improvement in the manufacture of fibrous material to be used as a substitute for leather and other purposes, which improvement consists in first introducing into the fabric to be impregnated a substance which is insoluble in the solvent used for the impregnation of the fabric with the filling material, impregnating the fabric with the solution of a suitable filling material and then introducing the thus filled fabric into a fused mass adapted to be dissolved by the solvent used in the said solution substantially as described.

3. An improvement in the manufacture of fibrous material to be used as a substitute for leather and other purposes, which improvement consists in first introducing into the fabric to be impregnated a solution of a

substance insoluble in the solvent used for the impregnation of the fabric with the filling material, removing the solvent for the said substance, impregnating the fabric with the solution of a suitable filling material and then introducing the thus filled fabric into a fused mass adapted to be dissolved by the solvent used in the said solution substantially as described. 70

4. An improvement in the manufacture 75 of fibrous material to be used as a substitute for leather and other purposes, which improvement consists in first introducing into the fabric to be impregnated a solution of a derivative of cellulose, drying out the solvent from the fabric and impregnating the latter again with the solution of a suitable filling material and then introducing the thus filled fabric into a fused mass adapted to be dissolved by the solvent used in the said solution substantially as described. 80

5. An improvement in the manufacture 90 of fibrous material to be used as a substitute for leather and other purposes, which improvement consists in first introducing into the fabric to be impregnated a solution of celluloid, drying out the solvent from the fabric and impregnating the latter again with the solution of a suitable filling material and then introducing the thus filled fabric into a fused mass adapted to be dissolved by the solvent used in the said solution substantially as described. 95

6. An improvement in the manufacture of 100 fibrous material to be used as a substitute for leather and other purposes, which improvement consists in first introducing into the felted fabric a solution of a suitable filling material and then introducing the thus filled fabric into a fused mass adapted to be dissolved by the solvent used in the said solution substantially as described. 105

7. An improvement in the manufacture of 110 fibrous material to be used as a substitute for leather and other purposes, which improvement consists in first introducing into a felted fabric, composed of a number of superimposed layers, a solution of a suitable filling material and then introducing the thus filled fabric into a fused mass adapted 115 to be dissolved by the solvent used in the said solution substantially as described.

8. An improvement in the manufacture of 120 fibrous material to be used as a substitute for leather and other purposes, which improvement consists in first introducing into the fabric to be impregnated a solution of a bituminous filling material and then introducing the thus filled fabric into a fused mass adapted 125 to be dissolved by the solvent used in the said solution substantially as described.

9. An improvement in the manufacture of 130 fibrous material to be used as a substitute for leather and other purposes, which im-

provement consists in first introducing into the fabric to be impregnated a solution of a bituminous filling material and then introducing the thus filled fabric into a fused bituminous mass adapted to be dissolved by the solvent used in the said solution substantially as described.

10. An improvement in the manufacture of fibrous material to be used as a substitute for leather and other purposes, which improvement consists in first introducing into the fabric to be impregnated a solution of petroleum pitch and then introducing the thus filled fabric into a fused mass adapted 15 to be dissolved by the solvent used in the said solution substantially as described.

11. An improvement in the manufacture of fibrous material to be used as a substitute for leather and other purposes, which improvement consists in first introducing into the fabric to be impregnated a solution of petroleum pitch in benzene and then introducing the thus filled fabric into a fused mass adapted to be dissolved by the solvent 25 used in the said solution substantially as described.

12. An improvement in the manufacture of fibrous material to be used as a substitute for leather and other purposes, which improvement consists in first introducing into the fabric to be impregnated a solution of a suitable filling material and then introducing the thus filled fabric into a fused mass consisting of petroleum pitch substantially 35 as described.

13. An improvement in the manufacture of fibrous material to be used as a substitute for leather and other purposes, which improvement consists in first introducing into the fabric to be impregnated a solution of petroleum pitch and then introducing the thus filled fabric into a fused mass consisting of petroleum pitch substantially as described.

45. 14. An improvement in the manufacture of fibrous material to be used as a substitute for leather and other purposes, which improvement consists in first introducing into the fabric to be impregnated a solution of a suitable filling material and then introducing the thus filled fabric into a fused mass consisting of a mixture of petroleum pitch

and linseed oil varnish substantially as described.

15. An improvement in the manufacture 55 of fibrous material to be used as a substitute for leather and other purposes, which improvement consists in first laying a felted fabric in a solution of petroleum pitch in an equal volume of benzene, transferring the 60 fabric when fully saturated with this solution to a molten mass consisting of 90-95 parts of petroleum pitch and 10-5 parts of linseed oil varnish, allowing the fabric to remain for about 24 hours in the molten 65 mass, the initial temperature being about 85° C. and the final temperature 100°-110° C., whereby nearly all the benzene is gradually expelled from the fabric while its place is taken by the molten mass and 70 allowing the finished piece to remain for about 14 days for hardening substantially as described.

16. As an article of manufacture, a fibrous mass impregnated with a cellulose derivative and a normally solid bituminous material. 75

17. As an article of manufacture, a fibrous mass impregnated with a cellulose derivative and petroleum pitch. 80

18. As an article of manufacture, a fibrous mass impregnated with celluloid and petroleum pitch.

19. As an article of manufacture, a fibrous mass, the fibers of which are coated with an 85 inner layer of a cellulose derivative and a layer above said inner layer of a normally solid bituminous material.

20. As an article of manufacture, a fibrous mass, the fibers of which are coated with 90 an inner layer of a cellulose derivative and a layer above said inner layer of petroleum pitch.

21. As an article of manufacture, a fibrous mass, the fibers of which are coated with an 95 inner layer of celluloid and a layer above said inner layer of petroleum pitch.

That I claim the foregoing as my invention, I have signed my name in presence of two witnesses, this fourth day of June 1914. 100

DR. PHIL. KURT HARING.
